METHOD OF REFORMING RAIL JOINT BARS

George Langford, Joliet, Ill.

Application December 14, 1936, Serial No. 115,660

9 Claims. (Cl. 29—169)

My invention pertains to rail joint bars, commonly called splice bars or angle bars, and is particularly directed to the reforming of bars worn from use.

5 The reforming of worn bars is now so commonly practiced as to require no explanation; but the successful continuance of that practice has made it not only desirable but necessary to develop new and more accurate methods to keep 10 pace with the exacting demands for a better product. The ordinary wear of a rail joint occurs mostly at its center portion particularly on the top fishing surface, and metal is actually worn away there so that the proper reforming 15 of the bar's worn central portion is interfered with by excess of metal at the end portions unless the dies commonly used are designed in a manner to counteract this difference. In the prior art it is known that a die cavity may be contracted in cross-sectional area at its central portion to counteract the central loss of metal, and it is also known that a die cavity may be expanded in cross-sectional area at its end portions so as to relieve the end portions of the bar 20 from excessive reforming pressure. In the present invention end relief may be gained without expanding the end portions, or contracting the central portion of the die cavity.

In the drawings:

25 Figure 1 is an end view of a bar being subjected to pressure in dies, illustrating the method of my invention;

Figure 2 is an end view of a bar before the method of my invention is applied;

30 Figure 3 is an end view of the bar of Figure 2 before, in dotted lines, and after, in full lines, treatment by my method;

Figures 4 and 5 are end views of a bar being reformed in dies according to my invention;

35 Figure 6 shows the bar in cross-section, made from the worn bar in dotted lines, by the method of Figure 4;

Figure 7 shows the bar in cross-section, made from the worn bar in dotted lines, by the method 40 of Figure 5;

Figure 8, comparable with Figure 1, illustrates the inverse of the method of Figure 1;

Figure 9 illustrates the inverse of the method of Figure 2;

45 Figure 10 shows the difficulties encountered in the prior art when reducing a bar's fishing height;

Figure 11, illustrating a pair of dies not fully closed upon a bar, shows how the difficulties 50 shown in Figure 10 are avoided;

Figure 12 illustrates the operation of Figure 11 with the dies closed; and

Figure 13 is a view similar to Figure 6, of a bar produced by the method of Figure 12.

In a broad sense I consider the bar's cross-section as an arch which I flatten out, thereby increasing its width or fishing height. In Fig. 1 a bar is shown in dotted lines, end view, as an arch, resting upon a bottom die 2. A top die 1 with pressure P moving from "z" to "z'" has 5 closed upon the arched bar, in dotted lines, flattening out the arch so that the bar becomes shaped as in the full lines. This flattening out of the arch moves surfaces $a-b$ and $c-d$ to $a'-b'$ and $c'-d'$, respectively, thereby materially 10 increasing the length of the arch, corresponding to the bar's fishing height.

In Fig. 2, the arched bar of Fig. 1, in dotted lines, is made to resemble more nearly the shape of a rail joint bar, but the principle of an arch 15 to be flattened out applies as in Fig. 1. Point "z" is the center of the web element. It is to be pushed down by pressure P . Surfaces $a-b$ and $c-d$ are to be pushed horizontally outward, not downward. This lateral spreading is a toggle 20 action, which does not require much pressure P , assuming that the web element is free to move 25 downward.

Surfaces $a-b$ and $c-d$ are free to move laterally but are restrained from downward movement. "x" and "y" are the centers of $a-b$ and $c-d$, respectively. Points "x" and "y" are free 30 to move laterally but not downwardly, and so if the web element is pushed downwardly, the arch represented by $x-z-y$ will be made flatter, 35 thereby spreading the fishing surfaces $a-b$ and $c-d$ outwardly and making the bar of increased fishing height. This is shown in Fig. 3, the original bar being in dotted lines, and the reformed bar in full lines. Maintaining the width 40 of a fishing surface, particularly the top one, is important. If possible, it should not be narrowed, thereby decreasing the width of rail fishing contact. The effect shown in Fig. 3 is the same as in Fig. 1. The web element is moved 45 downwardly. The head and foot elements are restrained from moving downwardly but are free to move outwardly as the arch $x-z-y$ in Fig. 3 is flattened to $x'-z'-y'$.

But there is more involved in actual practice 50 than merely flattening the original arch. After that, metal must be made to flow to restore the bar's centrally worn fishing surface; also the common angle form of bar is to be considered. A practical application of my invention is shown in 55

Fig. 4. This is an end view of a closed die cavity in full lines, 1 being the top die, and 2 the bottom die. The original bar is in dotted lines.

As surface $i-j$ of the web element is free to move downwardly, to at least $i'-j'$ of the die, there will be no direct reaction to pressure on surface $i-j$ and pressure P will be directed diagonally outward as per the arrow P' so that surfaces $b'-h'$ and $k'-d'$ of the bottom die will 10 bear the reactions to pressure.

The head element of the bar will now be considered. As the width of top fishing surface should not be decreased, the reaction to pressure P' should avoid the part surface $b'-e$ and 15 occur on $e-h'$. This actually does happen naturally. As the arch is flattened out, $e-h$ takes the reaction, as part width $b-e$ rides upwardly and outwardly. This avoids draughting the bar at $b-e$. But the flattening of the arch, rocks 20 the top element so that surface $a-b$ of the bar becomes of less angularity and more inclined to surface $a'-b'$ of the die; and at the same time, it tends to move upward. In Fig. 4 surface $e-h$ of the bar is draughted so as to cause flow 25 of metal; and this accentuates the previously mentioned difficulty of rocking the fishing surface $a-b$ of the bar up and out of its correct position.

Surface $a-f$ of the bar is now draughted by 30 the top die, so that when the dies are closed surface $a-f$ assumes the shape $a'-f'$ of the die. Point "a" is not draughted, so that as the dies close, the heavy pressure is at "f"; none at "a", although the pressure spreads towards "a" and 35 counteracts the upward rocking movement of "a" as compelled by pressure reaction on $e-h$; but the top pressure diminishing to "a" is a finely cushioned movement which pushes "a" gently to "a'" without draughting it and thereby narrowing 40 fishing surface $a'-b'$, the thing to be avoided.

More briefly, the method of my invention comprises two features. The arch is flattened to gain fishing height; and the draughts to move metal to restore a worn fishing surface, are so applied 45 as to counteract the upward rocking movement of a fishing surface as the arch is flattened, and to restore that fishing surface without narrowing it. This pertains particularly to the web and top element of a bar.

50 In the angle form of bar of Fig. 4, the narrowing of a bottom surface is not important. It is often desirable to narrow it or to shorten the inwardly extended part.

It will be noticed in Fig. 4, that surfaces $h'-i'$ 55 and $j'-k'$ of the die do not draught surfaces $h-i$ and $j-k$ of the bar. Nor does surface $i'-j'$ of the die draught surface $i-j$ of the bar. Hitherto draughts on surfaces $h-i$ and $j-k$ of the bar have been considered essential to push the 60 fishing surfaces opposite them back to increased height. As far as I know, nobody has tried any other way. But I do not so use these surfaces. I merely flatten the arch to gain height. But the bar must also be draughted, and I do this as 65 on surface $a-f$, with or without the draught on $e-h$, as the particular case may require.

In Fig. 4, the important thing to note is that the web element is pushed down and the fishing surfaces are spread outwardly. Surface $i-j$ of 70 the bar is pushed down to $i'-j'$. It may be pushed down farther so that the web element is draughted as may be required in some cases.

In Fig. 5 the bottom die 2 has no raised surface to engage surface $i-j$ of the bar. Surface 75 $i'-j'$ of the die cannot possibly touch surface

$i-j$ of the bar. This makes a very simple form of die. It also precludes the use of a die-lock at 3 as is shown in Fig. 4.

Flattening of the arch and the novel draughting at $a-f$ in Figs. 4 and 5, tending to move the 5 top fishing outwardly and also to restore it, preclude the necessity of draughting surface $h-i$ as in the prior art. The space between $h-i$ and $h'-i'$ then becomes a relief space, where excess metal at the end portions of the bar may escape. It may escape at the central portion also if there is an excess of metal there. This permits of longitudinally straight die walls; that is, die surfaces planed in straight from end to end or at least without any contraction of the die 10 cavity at center to counteract the loss of centrally worn metal.

The reformed bar does not conform closely to the die-cavity in cross-section. Fig. 6 represents the worn bar, in dotted lines, of Fig. 4 reformed in the die cavity of Fig. 4, to the finished bar of Fig. 6, in full lines and sectioned. The inner parts of the top and bottom elements are thickened vertically in the reformed bar, where metal has flowed into the relief space between 15 $h-i$ and $h'-i'$ in Fig. 4.

Fig. 7 shows similarly the result of the method of Fig. 5. This is merely a more elaborately treated example. The bottom element is considerably altered. But the features which I claim as new 20 are present in these and all other cases. Considered as an arch, the bar is flattened out to gain fishing height, and the surfaces ordinarily used to draught and gain fishing height, become 25 relief surfaces. Other surfaces are used for 30 draughting, and the draughting is applied in such 35 manner as to encourage spreading action, leaving the surfaces ordinarily used for spreading 40 purposes, free for relief purposes, so that excess 45 metal, usually at the end portions of the bar, 50 may escape, thereby avoiding excessive end 55 resistance to the reforming pressure. In Figs. 6 55 and 7, the outer face of the bar is moved inwardly, and the top fishing surface at least, is 60 moved upwardly, the bottom fishing surface being moved downwardly in most cases, and sometimes outwardly. As shown in Figs. 6 and 7, inward movement is directed to the web element, the top and bottom elements being restrained 65 from movement inward. This flattening of the 70 arch as I define it is a distinctly different operation from that of the prior art, which latter involves a stretching of the web which would occur 75 in Fig. 4 if the top and bottom elements of the 80 bar were draughted at $h-i$ and $j-k$, respectively. The present method does not draught 85 these surfaces but instead uses them as relief 90 surfaces where any excess of metal may escape, particularly at the less worn end portions of 95 the bar.

The draughting of surfaces other than the relief surfaces $h-i$ and $j-k$, is accomplished in a manner that suits the spreading action resulting from flattening the arch. In Fig. 4 the draughting pressure on the head element begins 60 near "f" and the reaction to that pressure begins 65 near "h". As the top die descends, the pressure increases near "f" and spreads decreasingly toward "a", the reaction spreading decreasingly 70 from "h" to "e". This has the effect of urging metal to move toward the die wall $a'-b'$. The pressure on $a-f$ also counteracts the tendency of surface $a-b$ of the bar to rock to a decreased angle as the arch is flattened. The web is pushed down; the top and bottom surfaces $a-b$ and $c-d$ 75

spread outwardly; and the pressure at $a-f$ and $g-n$ then forces surfaces $a-b$ and $c-d$ down to correct angles in their new positions conforming to the die-walls $a'-b'$ and $c'-d'$ respectively.

5 Briefly described, the method of my invention, as shown in Fig. 4, is one which flattens the arch and thereby spreads the worn part at least of the bar to greater fishing height, the web element being pushed downward, and the top fishing surface 10 face at least being restrained from downward movement, its movement in Fig. 4 being laterally outward. This I believe to be broadly new, as is also the use of surface $h'-i'$ or surface $j'-k'$ or both surfaces of the die as relief surfaces in 15 stead of as draughting surfaces to push the metal outward. While I find the method of draughting part surfaces $e-h$ and $a-f$ of the bar very effective, I may vary this as particular cases may require. I may also shape the top element of 20 the bar as shown, and shape the bottom element by some other method.

In the drawings, I show the bar lying on its inner face, and the pressure striking from the upper die on the bar's outer face. I may invert 25 the bar or I may make the bottom die the movable one. In the former case, the arch would be flattened by pushing the top and bottom elements downwardly, the outer face of the bar web being restrained from downward movement.

30 For a clearer understanding, in the claims, I will consider the bar as in its normal position, as that of Fig. 6. The web element may be pushed downward as in Fig. 4, or the top and bottom elements may be pushed upward as would be 35 the case if the bar and die cavity of Fig. 4 were inverted. But in either case, the resultant bar of Fig. 6 would have its web element pushed inward relative to the top fishing surface, and the claims are so worded, the bar being considered 40 as in its normal erect position when the reforming pressure is applied.

45 My consideration of a bar as an arch cross-sectionally is applicable to rail joint bars in general, although in some cases, as in a flat strap form, it may not be considered so. However, if one or both of the top and bottom elements has an inwardly extended part, it may, for my purpose, be defined as transversely arcuate.

The principle of flattening the arch to gain 50 height may be taken as a preliminary operation applicable to new bar manufacture as well as to worn bar reforming. It enables me to gain fishing height either at the worn part of a bar or throughout the bar as a whole. It may be used 55 in the same manner in the manufacture of new bars. But when the fishing height is gained, it is then necessary to reform the fishing surfaces. This second operation must be done to great accuracy and metal must be made to flow to the 60 fishing surface. The method of Fig. 4 described, combines the two operations; first a sort of bending operation which flattens the arch and gains fishing height; second, a finishing operation which draughts one at least of the top and bottom 65 elements, and causes metal to flow to a fishing surface. Preliminary to reforming the bar in the manner stated, it may be, and preferably is, heated to a suitable working temperature, as is known in the art.

70 My invention as previously described and illustrated may now be taken inversely for the purpose of decreasing instead of increasing the bar's original fishing height. Instead of flattening the arch, I make it more arcuate relative to the top 75 fishing surface at least.

In Fig. 8, comparable with Fig. 1 the bar is made more arcuate which has the effect of drawing the fishing surfaces $a-b$ and $c-d$ inward instead of forcing them outward so that the fishing height of the bar is lowered, not raised 5 as in Fig. 1. Fig. 9 illustrates this inversion comparable with Fig. 2. This increasing of the arch to reduce fishing height has advantages, two at least of which are of great practical value.

The ordinary procedure is shown in Fig. 10. 10

The bar being of greater fishing height than the die rides into the bottom die in a raised position, on surfaces $a-b$ and $c-d$, and jams on these surfaces so that it is difficult to draw the bar into position in the bottom die. This has the effect of wearing the die longitudinally. There is also transverse wear on surfaces $a-b$ and $c-d$ of the die when the reforming pressure forces the bar down into the bottom die on these surfaces. They wear rapidly as a result, and the tonnage ordinarily producible is greatly curtailed, requiring frequent truing up of the dies in the planer because of destructive wear. This may be remedied as in Fig. 11. 15

20 In Fig. 10, surface $i-j$ of the bar does not touch surface $i'-j'$ of the die, but in Fig. 11 it does because of the provisions in the bottom die for displacing the web element upwardly relative to the fishing surfaces. The bar slides readily into the bottom die on surface $i-j$ instead of on surfaces $a'-b'$ and $c'-d'$, and the wear on surfaces $a'-b'$ and $c'-d'$ is greatly reduced. Fig. 25 25 shows what follows in Fig. 11 when the dies are closed upon the bar, and when compared with Fig. 4, illustrates the inversion of the flattening of the arch as first described.

30 Fig. 13 shows the original bar in dotted lines, and the reformed bar in full lines, sectioned.

35 Inasmuch as the bottom fishing surface of an angle form of bar, is, unlike the top fishing surface, often preferably narrowed and otherwise altered, a change in the arch is not as obvious at the bottom of a bar as it is at the top. It may be noted however, that in all cases, the outer bolting face at least of the bar is moved inward or outward in relation to a fishing surface, and this is applicable to the bottom fishing surface; furthermore the outer bolting face may be only a 40 part and not all of the outer web face. 45

45 Instead of moving the web inward or outward 50 I may move the top element or bottom element or both inward or outward but these movements must change the position of a fishing surface relative to the outer bolting face. In this, I distinguish from the method of my Patent No. 1,833,026 issued November 24, 1931, wherein the bar, outer bolting face and all, is tilted so as to move the top element inward and the bottom element outward, or vice versa. This patent shifts the top element inward and the bottom element 55 outward in respect to the rail but not in respect to the bar's outer bolting face. The bar as a whole is merely inclined to the rail which is quite different from the present disclosure. 60

65 Fig. 12 is the same as Fig. 11, excepting that where in Fig. 11, the dies are nearing closure, they are finally closed in Fig. 12. The original bar is in dotted lines, and the die cavity in full lines. The draughts shown on $e-h$ and $a-f$ are intended to insure flow of metal to surface $a'-b'$. 70 These and other surfaces may be used either for relief or for draughting purposes as different cases warrant. The bottom element of the bar may be treated in the same manner, or both the top and bottom elements may be so treated. 75

Considering the bar in its upright, installed position, as in Figs. 6 and 13, my method is one wherein the web element of the bar is displaced inwardly or outwardly relative to the top or bottom element or both, to increase or decrease the bar's fishing height. More particularly, the web element is displaced laterally relative to the top or bottom fishing surface or both, and this displacement is indicated by change of position 10 of the outer face of the web element or at least that part of the outer face which engages the head of the joint bolt, nut or washer. To insure displacement of metal under pressure, the bar is first heated to a working temperature and then 15 shaped in dies, rolls or any other means that accomplish my purpose.

I claim:

1. The method of reforming a worn rail joint bar, which comprises heating the bar to a working temperature and subjecting it to reforming pressure, said pressure being applied so as to force the web element inwardly, one of the top and bottom fishing surfaces of the bar being restrained from inward movement, and said inward movement of the web element relative to said one of the top and bottom fishing surfaces, raising a worn portion of said one fishing surface to increased fishing height.
2. The method of reforming a worn rail joint bar, which comprises heating the bar to a working temperature and subjecting it to reforming pressure, said pressure being applied so as to force the web element inwardly, the top fishing surface being restrained from inward movement, 35 and said inward movement of the web element relative to said top fishing surface raising a worn portion of the top fishing surface to increased fishing height.
3. The method of reforming a worn rail joint bar and its top fishing surface, which comprises heating the bar to a working temperature and subjecting it to reforming pressure, said pressure being first applied so as to force the web element of the bar inward relative to said fishing surface 45 so as to move said fishing surface to increased fishing height, said pressure being then applied upon one of the inner and outer faces of the top element so as to effect a flow of metal to said fishing surface, the inner-under surface of the bar opposite said fishing surface being relieved from said pressure and providing an outlet for flow of excess metal in said member.

4. As a preliminary operation in the manu-

facture of rail joint bars, the method which comprises heating the bar to a working temperature and subjecting it to pressure effective to displace the web element inwardly in relation to the top fishing surface, thereby effecting an increase in 5 the bar's original fishing height.

5. The method of reforming a worn rail joint bar and one of its top and bottom fishing surfaces, which comprises heating the bar to a working temperature and subjecting it to reforming 10 pressure, said pressure being first applied so as to displace the web element of the bar outwardly relative to said fishing surface so as to move said fishing surface to decreased fishing height, said pressure being then applied upon one of the inner 15 and outer faces of the element including said fishing surface so as to effect a flow of metal to said fishing surface, the inner surface of the bar opposite said fishing surface being relieved from said pressure and providing an outlet for flow 20 of excess metal in said element.

6. The method of reforming rail joint bars, which comprises heating the bar to a working temperature, and subjecting it to pressure effective to displace the web element laterally in relation to the top fishing surface, thereby effecting a change in the bar's original fishing height.

7. The method of reforming rail joint bars, which comprises heating the bar to a working 30 temperature, and subjecting it to pressure effective to displace the web element outwardly in relation to the top fishing surface, thereby effecting a decrease in the bar's original fishing height.

8. The method of reforming a worn rail joint bar, which comprises heating the bar to a working temperature, and subjecting it to reforming pressure, said pressure being applied so as to displace the web element laterally relative to the top fishing surface, said repositioning of said web 35 element changing the bar's fishing height.

9. The method of reforming the top element and included fishing surface of a rail joint bar, which comprises heating the bar to a working temperature, and subjecting said top element to reforming pressure, said pressure being first applied to displace the web element of the bar laterally relative to said fishing surface thereby effecting a change in the bar's original fishing height; said pressure being then applied to said top element so as to effect a flow of metal to 45 50 said fishing surface.

GEORGE LANGFORD.
